EDWIN BALTZLEY, OF GLEN ECHO, MARYLAND.

PAPER-HOLDING CLIP.

1,236,654.

Specification of Letters Patent. Patented Aug. 14, 1917.

Application filed June 21, 1916. Serial No. 104,904.

To all whom it may concern:

Be it known that I, EDWIN BALTZLEY, a citizen of the United States, and resident of Glen Echo, county of Montgomery, and 5 State of Maryland, have invented certain new and useful Improvements in Paper-Holding Clips, of which the following is a specification.

My invention relates to paper holding 10 clips, and has for its object to produce a clip of great cheapness, simplicity, efficiency, wide application and of strong holding powers, in which the paper is inserted in the clip from the back and without the need of 15 any spreading means other than that secured by direct pushing, turning and wedging action in putting the clip in place on the papers to be bound.

All clips heretofore, so far as I am aware, 20 have been made to admit the papers at the open or jaw side, which called for special mechanism or entrance means, in some cases expensive and in other cases otherwise faulty, especially in the paper fastener class 25 designed for holding together a comparatively small number of papers, in so far that all of them have been so constructed that after they have been applied to a bunch of papers other papers could slip under the 30 jaws and be carried off and lost.

In my clip the jaws are held tight together and the entrance of the papers to them is from the rear instead of from the front or jaw side of clip, thus reversing previous 35 practice. Preferably I cut away a portion of the back or spring member, and through the opening thereby made admit the papers and force them between the converging sides toward the jaws, thus wedging the jaws 40 apart until the papers pass through the jaws, whereupon the clip is then turned forward and downward until it has reached its proper seat upon the papers, and the jaws continue to tightly bind the papers so that 45 no other paper can possibly get under them and be carried off and lost. This is one of the distinctive features of all varieties of my clip.

The rear entrance also dispenses with the 50 necessity of all other means of spreading the jaws, some of which are expensive and others clumsy. This rear entrance is also a gage of the quantity of papers the clip is designed to bind. In all clips made to be opened by le- 55 vers or pliers, it requires care not to expand

the sides of the clip beyond their elastic limit and lack of such care frequently results in breaking the clip. No such thing is possible with my clip because the sides cannot be expanded beyond the size of the rear 60 entrance. The clip, therefore, is reduced to the maximum of simplicity and cheapness, its preferable form being but a single piece of sheet metal stamped and bent to substantially triangular form as viewed from one 65 end and having provision for rear entrance of the papers to be bound or held.

With the foregoing and related objects in view, my invention consists in the improvements and features of construction herein, 70 after referred to.

In the accompanying drawings, forming a part of this specification, and wherein the same reference numerals are applied to the same parts throughout, Figure 1 is a view 75 in perspective of one form of clip embodying my invention and a bunch of papers and showing the relation of the clip thereto at the beginning of its application, the edge of the papers being shown in one position in 80 full lines and in another position in dotted lines. Fig. 2 is a view similar to Fig. 1 but showing the clip of Fig. 1 in place on the bunch of papers. Fig. 3 is an end view of the clip of Figs. 1 and 2. Fig. 4 is a cross- 85 sectional view on line 4-4, Fig. 3. Fig. 5 is a perspective view of a modified form of clip having the means for rear entrance provided on one end only and showing a reinforcing means for the spring back. Fig. 6 90 is an end view of the clip shown in Fig. 5, but with the jaws spread somewhat farther apart initially to accommodate greater thickness of papers to be bound. Figs. 7 and 8 are perspective views of a further 95 modified form of clip, Fig. 8 illustrating the preferred mode of placing the clip of Fig. 7 upon a bunch of papers to be bound. Fig. 9 is a perspective view illustrating the clip of Fig. 7 with the lever attachment temporarily 100 secured in place on one of the jaws. Fig. 10 is a perspective view of a modified form of attachable or removable lever which may be utilized in the manner shown in Fig. 9. Fig. 11 is a perspective view of a clip similar to 105 the clip of Fig. 5 but with more material cut out of the back and without reinforcement. Fig. 12 is a perspective view of a clip generally similar to the clip of Fig. 1, but formed of wire and illustrating its mode 110

of use in connection with a bunch of papers. Fig. 13 is a perspective view of a modified form of wire clip having but one rear entrance. Fig. 14 is a perspective view of a 5 clip generally similar to the clip of Fig. 13, but formed of sheet metal. Fig. 15 is a front view of a clip similar to the clip of Fig. 1, but having circular jaws. Fig. 16 is an end view of the clip of Fig. 15. Fig. 17 is a 10 face view of a clip like that shown in Fig. 15, but provided with a fastening tack. Fig. 18 is an end view of the clip of Fig. 17, and Fig. 19 is a perspective view of a clip such as shown in Fig. 15 but having a pair of 15 marginal holding tacks.

The clip of Fig. 1 is made of spring sheet metal. Other materials may, of course, be used. Preferably the upper and lower clamping members, designated at 10 and 11, 20 are substantially identical in form, though this is not essential. These members 10 and 11 converge toward their free edges 12 and 13 and diverge at the rear, as indicated at 25 14 and 15. The space 16 between the rear portions 14, 15 thereof varies according to the size of the clip and the maximum thickness of the bunch of papers to be held, as will be understood. The clamping members 10 and 11 are connected at their rear parts 30 14 and 15 by a spring member which tends to press their free edges 12 and 13 toward one another. In the form illustrated, the spring member is shown at 17 and is integral with the clamping members 10 and 11, all the 35 parts being, in the form shown, made of one integral piece of sheet spring metal which is preferably tempered after it has been formed up. The front and side edges of the clamping members 10 and 11 are 40 preferably flared slightly, as shown best in Figs. 3 and 4, and this flaring is most conveniently provided by bending the edges outwardly and extending the bend of the edges around the clip from one side of the 45 back to the other, as shown clearly in Figs. 1 and 2 and indicated at 18. Displacement of the material effected by such bending action extends through the material of the clamping members, and papers placed there- 50 in are clamped a short distance back of the edges. This flaring of the edges is only necessary when the clip is made of tempered steel or stiff metal, whereby the clamping tension is necessarily great. It is not re- 55 quired in clips that do not need great clamping tension, such as those of the paper fastener class.

The entrance of the bunch of papers into 60 this clip is from the rear thereof, as clearly indicated in Fig. 1, and means for securing easy direct insertion of a bunch of papers into the clip at its rear is provided, the clip being turned on the papers (or con- 65 versely the papers in the clip) in the direction of the arrow in Fig. 1, so as to bring

the clip into its correct holding position as shown in Fig. 2. The bunch of papers 19 is shown in an additional position in Fig. 1 at 19' in dotted lines, so as not to confuse the showing of the construction of the clip 70 itself.

In the form shown, the rear entrance is provided by cutting away the spring back piece 17 as shown at 20, making it shorter than the longest portion of the clamping 75 sides. I have shown the cut away part 20 provided at both ends of the clip, though it is not essential that more than one of the ends be cut away to provide entrance from the rear. The corners 21, 22 of the clamp- 80 ing members 10 and 11 in the neighborhood of the cut-out 20 are preferably extended somewhat, as shown, and flare outwardly so as to facilitate the entrance of papers from the rear between the clamping members 10 85 and 11.

Figs. 5 and 11 show a larger clip adapted to a book or bunch of papers ranging up to a capacity of say about $\frac{5}{8}$ " to $\frac{3}{4}$ " in thickness and having means for rear entrance at 90 one end only. Up to about $\frac{3}{8}$ " capacity the form shown in Fig. 1 readily adapts itself because the angle of convergence of the sides 10 and 11 is very slight and admits of the acute triangular form shown in Figs. 1 95 and 4. But the greater angles are best pro- 23 vided for in the forms shown in Figs. 5 and 11. The entrance slot in the spring back or base 17 of Fig. 5 is deeper or larger and the ends of the clip are rounded as at 100 23 to a true circle. This gives a more easy and gradual wedging action of the inserting papers on the converging sides of the clip. Moreover, I make this clip of fairly thin metal so that it will be easier to spread the 105 jaws by the wedging papers and rely on a larger clip with greater length of spring back to give the necessary gripping tension of the jaws, and to this end I only slot one end of the clip.

In the form shown in Fig. 5, to avoid possible breakage of the back when placing the clip on a book or bunch of papers, I may reinforce the back substantially as shown by forming a comparatively narrow 115 slot 24 which may be rounded at its inner end, as at 25, and the material cut back on either side, as at 26, and bent under to form reinforcing means 27, 27 in the opening, between which the rear entry of the papers 120 to be bound may be effected. Such construction assures a smooth and noncutting edge.

Or I may cut away the entire back at the end, as shown at 28, Fig. 11, and to avoid breakage may round the corners preferably 125 with rounded recesses, as shown at 28. This provides great flexibility and ease of entrance for the papers to be bound and the jaws may readily be spread apart by the wedging action of the papers entering the 130

cut-away part 28 to substantially its full extent when introduced from the rear of the clip.

The clip with the rear entrance opening 5 can be made of wire, as shown in Figs. 12 and 13. In Fig. 12 the jaws are indicated at 10' and 11', and the back is formed by twisting the wires together as at 32. In the construction shown in Fig. 13, the two jaws 10 are indicated at 10" and 11", and the spring back is formed centrally of the piece of wire from which the clip is formed, as indicated at 33. A very simple and cheap form from stamped metal with the same rear opening 15 principle can be made, as shown in Fig. 14, and is included in the paper fastener class. In this figure the jaws are marked 10^a and 11^a, and the spring back is shown at 34.

Still another form of paper fastener with 20 the rear entrance opening I show in Figs. 15, 16, 17, 18 and 19. It is preferably bent from a true circular stamping of brass or untempered steel. Because the capacity of this class of fasteners is always small, wherever 25 in the converging angle of the sides is very slight, no flaring of the edges is necessary. It takes the place of all that class of clips that surreptitiously pick up foreign papers.

This flat rounded surface 35, 35' of the 30 jaws also especially lends itself for advertising purposes, in its large sizes, as shown in Figs. 15 and 19. Also for permanent binding of legal papers, wherefor one or more tacks are stamped and bent to form from one 35 of its sides, and a concave depression formed in the opposite side to house the points of the tacks, as shown in Figs. 17, 18 and 19. The point of the tack is held just above the inside plane of the side of the clip so as not 40 to interfere with the use of the clip as a pressure binding clip, and may be so held indefinitely until it is desired to fasten the papers permanently, when the tack can be readily and quickly pushed through the 45 papers by thumb pressure.

One form of such tack is shown at 36, in 50 Fig. 18, and is formed by stamping out the metal as shown at 37', leaving an intermediate space between the tack 36 and the cut margin 37 so that proper clearance for the tack may be provided. The back may be recessed, as at 37, Fig. 18, to receive the point of the tack 36, or the tack may be formed in the margin at any convenient 55 point, a pair of such tacks located in the margin of one of the clip jaws being illustrated at 38, 38, Fig. 19. In Figs. 9 and 10 I have shown two forms of detachable levers which may be secured to clips such as shown 60 in Figs. 7, 8 and 11, or to other forms of clip. These levers comprise preferably a handle 39 and means of attachment to the clip, and such attaching means may comprise the turned over edge 40 and securing 65 lugs as 41, 42, shown in Fig. 9, or instead of

turning both lugs under, as shown in Fig. 9, one of them, as 43, Fig. 10, may be turned down square, the remaining lug 44 being relied on with the turned over edge to hold the lever in place and the lug 43 coöperating therewith to prevent relative action between the lever and clip and to facilitate attachment and removal. The lever 39' of Fig. 10 is provided with a cut out part 45 in that portion of it which rests against the 70 clip jaw, and such detachable levers may be of various other constructions, as will be readily understood, so long as they can be readily attached and removed. While in Fig. 9 such lever is shown secured to one of the jaws, it will be obvious that they may be secured to each jaw if desired, although ordinarily by pressing against one jaw and against the extended lever on the other jaw the clip may be opened to permit insertion 80 and removal of papers.

The operation of a clip in accordance with my invention will be readily understood from the foregoing. Clips varying in thickness being provided and one having been 90 selected of a proper thickness for the bunch of papers to be bound, or a bunch of papers of lesser thickness, since each clip is preferably designed to take all thicknesses of papers up to its maximum and hold it firmly, 95 the papers are introduced at the rear. In the case of the clip of Fig. 1 the papers are inserted into the opening between the spreading points 21, 22 at the rear of the clamping members 10 and 11, and having obtained entrance in this manner the clip is readily pushed thereon and turned at the same time to hold the papers, as shown in Fig. 2, the clamping members 10 and 11 separating as 100 the clip is pushed on the papers and the 105 flared edges outside the grooves 18 serving to facilitate the entry and movement of the clip with respect to the paper, as they prevent the paper from making any contact with the extreme edges of the clamping members 10 and 11, presenting a rounded surface 110 near the free edges which takes the bearing contact of the clip with the paper.

It will be seen that a clip in accordance with my invention is very readily and 115 cheaply constructed, will hold papers firmly and securely and is readily put in place, and with the papers being inserted from the back there is no loss of holding power, which may result when the papers are otherwise 120 introduced.

It is to be understood that changes and modifications may be resorted to within the scope of my claims and without departing from or sacrificing the advantages of my 125 invention.

Having thus described my invention, I claim:

1. A clip having members ending in clamping jaws, a spring back connecting 130

- said members and cut away at an end thereof to form an opening with said members for the entrance of papers therethrough to said clamping jaws.
- 5 2. A clip having converging sides with slightly flared edges and ending in clamping jaws, a spring back connecting said converging sides and cut away at an end thereof to form an opening with said sides for the entrance of papers therethrough to said clamping jaws.
- 10 3. A clip triangular in cross-section, the converging sides of which end in clamping jaws, a spring back connecting said converging sides and cut away at an end thereof to form an opening with said sides for the entrance of papers therethrough to said clamping jaws.
- 15 4. A clip triangular in cross-section, the converging sides of which end in clamping jaws, a spring back connecting said converging sides and cut away at an end thereof to form an opening with said sides for the entrance of papers therethrough to said clamping jaws.
- 20

ing jaws, one of the converging sides being 25 provided with a tack to be forced through the papers held between the said sides.

5. A clip having clamping sides ending in clamping jaws, a spring back connecting said clamping sides with an opening in an 30 end thereof between said sides for the entrance of papers therethrough to said clamping jaws, whereby the clip may be fastened on said papers to bind them by turning it.

6. A clip having clamping sides ending in 35 clamping jaws at the front thereof and in a spring back at the rear, said spring back which directly connects with said clamping sides being shorter than the longest portion of said clamping sides, forming thereby a 40 permanent opening from the rear of the clip for the entry of papers therethrough to and between said clamping jaws.

In testimony that I claim the foregoing, I hereto set my hand, this 20th day of June, 45 1916.

EDWIN BALTZLEY.
